UNITED STATES PATENT OFFICE.

OSCAR H. PIEPER AND ALPHONSE F. PIEPER, OF ROCHESTER, NEW YORK.

DENTAL EQUIPMENT STAND.

Application filed November 21, 1922. Serial No. 602,414.

This invention relates to dental apparatus and more particularly to dental equipment stands of the type adapted to support a variety of dental equipment adjacent the dental chair and within convenient reach of the dentist, the chief object of the invention being to provide a simple and practical stand of the above type capable of supporting a considerable variety of equipment in convenient arrangement and of being manufactured at a moderate cost. To these and other ends the invention resides in certain improvements and combinations of parts all as will hereinafter be more fully described, the novel features being pointed out in the claims at the end of the specification.

In the drawings:

Figure 1 is a front elevation of an equipment stand embodying the present invention;

Figure 2 is a side elevation of the same with parts broken away;

Figure 3 is an enlarged sectional view on the line 3^a—3^a of Figure 1;

Figure 4 is an enlarged detail view of the upper portion of Figure 3 with additional parts in section;

Figure 5 is a top plan view of the base portion of the standard and associated piping substantially as seen from the line 5^a—5^a in Figure 6;

Figure 6 is a view similar to Figure 1 enlarged and in central section to illustrate the interior construction and arrangement;

Figure 7 is a fragmentary detail view showing a modified arrangement of the parts, and

Figure 8 is a fragmentary detail view of a modified form of construction;

Similar reference numerals throughout the several views indicate the same parts.

The preferred embodiment of the invention disclosed herein by way of illustration comprises a hollow supporting column or standard 10, Figures 1 and 6, preferably in the form of a casting resting at its bottom on a base 11 having an opening 12, Figure 2, at one side thereof and sustaining the bottom of the column in spaced relation with the floor for the extension of piping into the column through its open lower end. The column branches at its top into three hollow bracket arms 13, 14 and 15 as shown, each for supporting different dental equipment as hereinafter described. These arms are pref-

erably arranged substantially in a plane parallel with the front of the column, or, in other words, with the side of a dental chair so as to dispose the various equipment carried by the arms adjacent the point of use and within convenient reach of the dentist and this arrangement incidentally affords a pleasing general symmetry in the appearance of the stand.

Arm 13, projecting laterally and upwardly at the right hand side of the column, is hollow as shown, preferably having fixed in its vertical upper end a hollow sleeve or post 16, Figure 6, on which is pivotally supported a substantially horizontal arm 17 above 70 which is pivotally supported also a curved motor bracket 18. Arm 17 preferably carries at its end a hollow trunnion 19 extending upwardly and pivotally supporting a horizontal arm 20 on the outer end of which is rotatably supported a frame 21 mounting an instrument tray 22. Trunnion 19 is preferably continued upwardly in the form of a tube 23 at the upper end of which is carried a Bunsen burner 24 of the usual or any suitable variety for apparatus of this nature. The gas for the burner is supplied through flexible tubing 25 connected with the lower end of trunnion 19 and trained along arm 17 and downwardly of arm 13 into connection with a controlling valve 26 carried by arm 13 and having a nipple extending into the latter through which the gas pipe is extended into and downwardly of the column as hereinafter described.

The motor bracket 18 is curved as shown to encircle the motor shown at 27 and pivotally support the latter and the attached engine arm 28 by a connection therewith indicated generally at 29. The motor being arranged on one side of the pivot 29 and the engine on the other, these parts effectively balance each other as well understood in the art. At 30 on the outer end of the engine arm is the usual handpiece for holding and operating the instruments. The electrical conductors for the motor are carried from the column interior through arm 13, post 16, and bracket 18, but are only shown in the present instance within the column as 105 this arrangement is well understood in the art.

The intermediate arm 14 extends upwardly substantially centrally of the column and has fixed in its upper end a sleeve or hollow 110

post 31 on which is pivotally supported a hub 32 carrying a shelf or tray 33 which normally projects toward the front of the casing. This tray may be used for supporting various equipment and is primarily intended in the present instance for supporting a receptacle 34, Fig. 1, for a pair of spray bottle holders 35 and a hot water container 36. At 37 is shown a spray bottle having a spraying or atomizing head 38 connected by means of flexible tubing 39 with a valve 40 fixed in the wall of arm 14 and extending interiorly of the latter into connection with an air supply pipe described hereafter.

Post 31 is continued upwardly above tray 33 and pivotally supports at its lower end an upwardly and rearwardly inclined extension 41 on the rearwardly offset upper end of which is pivotally supported a substantially horizontal, forwardly extending arm 32 carrying a tray 43 for instruments, supplies and other equipment. Extension 41 projects above arm 42 and has mounted thereon a sleeve 44 in which is fixed the socket portion 45 of a separable electrical connection, the plug portion 46 of which is fixed in a cup 47 adapted to be fitted onto sleeve 44 with the plug and socket parts guided into proper association by a pin 48 in sleeve 44 and a slot 49 in cup 47. The latter carries an upwardly extending conduit 50 flexibly jointed as indicated in Figure 1 and supporting a spot light 51 for convenient universal adjustment. An electrical conductor 52 is connected with socket member 45 and carried through extension 41, the hollow post 31 and arm 14 into and downwardly of the column, for disposition as hereafter described. The lamp is thus detachably mounted on extension 41 and in fact the latter and tray 33 also may be removed from arm 14 if so desired after withdrawing conductor 52.

The hollow cuspidor arm 15 is extended laterally at the left hand side of the column, Figure 6, with its open upper end disposed horizontally as shown. Secured on a seat 53 formed in this end of the arm is an elbow fitting 54 having a portion extended upwardly above the end of the arm and rotatably secured as by means of a union nut 55 to a hollow rotary head 56. The latter carries concentrically on its upper end the cuspidor 57 which discharges into the head 56 and the latter has a laterally extended hollow arm 58 provided with a holder 59 for a drinking glass 60 and with a waste basin 61 discharging into the hollow arm 58 and head. This construction is substantially as shown and described in Letters Patent No. 1,300,868, issued to us jointly April 15, 1919, for dental cuspidor fixtures, except that the head 56, instead of discharging directly into the hollow arm 15, discharges into a waste or discharge pipe 58^a connected with the head

by means of the attached fitting 54. The head 56 is thus rotatably supported on column arm 15 and the water discharged into the head is carried off by pipe 58^a which extends through the arm 15, into and downwardly of the column as shown. At 59^a is a water supply pipe for the cuspidor and the usual faucet 60, this pipe being pivotally connected by union means 61^a with a valve 62 fixed in the arm 15 so as to have a swinging movement about an axis concentric with that of head 56. From valve 62 a water supply pipe 63 extends through arm 15 and into and downwardly of the column.

At 64, Figure 6, is an insulating conduit carrying the electrical conductors for the lamp and for the motor to which parts the conductors are carried through their respective arms 14 and 13. At 65 within the column and arm 13 is a pipe for supplying gas to valve 26 controlling the burner on arm 17. At 66 within the column and arm 14 is a pipe for supplying air under pressure to valve 40 controlling the spray bottle apparatus. The electrical conduit and these various fluid pipes all extend downwardly within the column to a bridge plate 67 on top of the base 11 through which they extend and to which they are secured. Within the base these various pipes are directed laterally along the floor by means of elbow fittings and out of the base opening 12 for connection with their respective source of supply. The conductors are all thus carried within and concealed by the hollow column and its hollow arms except of course adjacent the points of application to the equipment supplied thereby. This construction not only protects the pipes but preserves the simplicity of line of the stand. At 68, Figure 1, is a conductor extended exteriorly of the column for connection with the usual foot control means for the motor.

In Figure 7 is shown a modified form of assembly in which the extension 41 of the intermediate arm 14 is removed and the upper end of post 31 covered and finished off by a cap 69, leaving tray 33 on the arm as described above, the electrical conductor 52 being for this purpose disconnected and withdrawn. Figure 18 shows a modified form of construction in which the extension 41 and the tray 33 of arm 14 are removed and a shorter extended portion 70 substituted having its upper end fitted to receive the lamp socket as previously described in connection with arm extension 41. This latter arrangement thus eliminates the trays 33 and 43 previously described.

It is apparent from the description and drawings that the present stand is a comparatively simple one having a practical form of construction which may be manufactured at a moderate cost. The parts are advantageously arranged to support all the

equipment within convenient reach adjacent the dental chair. The apparatus is furthermore compact and economical of space and has a general symmetry and simplicity of 5 line rendering it pleasing in appearance.

We claim as our invention:

1. In a dental equipment stand, a hollow column branching at its top into three hollow bracket arms, one for a motor and one 10 for a cuspidor, a pair of equipment trays movably carried in vertically spaced relation by the third arm for horizontal adjustment, and electrical and fluid conductors extended through said arms for connection with 15 equipment carried thereby.
2. In a dental equipment stand, a hollow column branching at its top into three hollow bracket arms, one for a motor and one for a cuspidor, a rearwardly offset upper 20 portion on said third arm provided at its top with means for supporting a lamp, a pair of trays pivotally supported in spaced relation on said third arm, and electrical and fluid conductors carried upwardly from the 25 base of said column through said arms for connection with equipment carried thereby.
3. A dental equipment stand comprising a hollow column having hollow projecting arms for a motor and a cuspidor, respectively, 30 an additional hollow arm projecting from said column, a tray carried by said additional arm, an upwardly and rearwardly inclined extension pivoted on said additional arm, detachable means at the upper end of 35 said extension for supporting a lamp, electrical conductors extended through said column and motor and additional arms, and fluid conductors extending through said column and cuspidor arm.
4. A dental equipment stand comprising a hollow column having hollow projecting arms for a motor and a cuspidor, respectively, an additional hollow arm projecting from said column, a tray carried by said ad-

ditional arm, an upwardly and rearwardly inclined extension pivoted on said additional arm, an arm pivoted adjacent the upper end of said extension, and a tray carried by said pivoted arm. 45

5. A dental equipment stand comprising a hollow column having hollow projecting arms for a motor and a cuspidor, respectively, an additional hollow arm projecting from said column, an upwardly and rearwardly inclined extension pivoted on said additional arm, a tray pivotally supported adjacent the upper end of said extension, detachable means adjacent the upper end of 50 said extension for supporting a lamp, electrical conductors extended through said column and motor arm and additional arm and extension for connection with equipment carried thereby, and fluid conductors extended through said column and cuspidor arm for connection with the latter. 55

6. A dental equipment stand comprising a hollow column branching at its top into three hollow bracket arms, a motor on one of said arms, a cuspidor on another of said arms, a hollow post carried by the third arm, 60 a tray pivotally supported on said post, a hollow extension pivotally supported on said post, and a lamp carried by said extension. 65

7. A dental equipment stand comprising a hollow column branching at its top into three hollow bracket arms, a motor on one of said arms, a cuspidor on another of said arms, a hollow post carried by the third arm, 70 a tray pivotally supported on said post, a hollow extension pivotally supported on said post, an instrument tray pivotally supported on said extension, a lamp on said extension and electrical connections for said lamp extending through said hollow post and extension. 75
